UNITED STATES PATENT OFFICE.

ANDREW E. ANDERSON, OF BROWNSVILLE, TEXAS.

ELEVATED DRAFTING-RULE.

1,213,813.

Specification of Letters Patent. Patented Jan. 30, 1917.

Application filed March 10, 1916. Serial No. 83,282.

To all whom it may concern:

Be it known that I, ANDREW E. ANDERSON, a citizen of the United States, residing at Brownsville, in the county of Cameron and State of Texas, have invented certain new and useful Improvements in Elevated Drafting-Rules, of which the following is a specification.

This invention relates to new and useful improvements in an instrument for the drafting or ruling of straight lines, which is an elevated drafting rule with various attachments and provisions, as hereinafter described, designed to attain the objects stated as follows: To provide a drafting rule which 10 being elevated above the surface of the drawing may therefore be placed over freshly inked and undried lines or figures and used for the ruling of new lines; to provide the means as hereinafter described, of raising 15 and lowering the ruling edge or straight edge of said rule so that without lifting the rule from the drawing, said ruling edge or straight edge may be raised and shifted to a new position without the danger of its smearing the undried ink underneath; to provide 20 a drafting rule, which, when being shifted or slid over the surface of the drawing, will be in contact with said surface at only four places, each of almost negligible area, thus preventing the drawing paper or cloth from 25 being rubbed and soiled as when an ordinary triangle or rule is used; to provide in connection with the straight edge of said rule, means of pressing and holding the drawing 30 paper or cloth firmly against the surface of the drafting table or board, immediately at each end of the line to be ruled and thus procuring a firm surface upon which to draw; 35 and by the same means to provide against the tendency of the rule to slip when in use, caused by the pressure of the pen or pencil or other instrument upon the straight edge of the rule.

40 With the above and other objects in view the invention has particular relation to certain novel features of construction, operation and arrangement of parts, an example of which is given in this specification and 45 illustrated in the accompanying drawing, wherein:—

Figure 1 is a perspective view of the rule, Fig. 2 is a top plan view, Fig. 3 is a bottom plan view, Fig. 4 is a transverse sectional view taken on the line $a-a$ of Figs. 2 and 3, Fig. 5 is a transverse sectional view taken

on the line $b-b$ of Figs. 2 and 3, and Fig. 6 is a longitudinal sectional view taken on the line $c-c$ of Figs. 2 and 3.

Referring now more particularly to the drawings wherein like numerals of reference 50 designate similar parts in each of the figures the numeral 1 refers to the rule proper and is a rectangular body preferably formed of glass or some other suitable rigid transparent material and which has the straight edge 2. Metallic plates 3 and 4 are crimped over the respective ends of this rule and upstanding from the former of which is the knob 5 by means of which the rule may be 55 lifted and moved. An oblong groove 6 extends from end to end of the rule along its upper side and near the edge opposite the straight edge 2 and parallel with said straight edge 2, and slideable in this groove 7 is the guide 7, upstanding from which is the pin 8 by means of which said guide may be 60 moved back and forth in said groove; and a flexible strap 9 is integral, at one end, with said guide and is bent around underneath 65 the rule and rests closely against the under side thereof, its free end extending as closely as may be to the straight edge 2 of the rule, the bent portion of said flexible strap 9 forming a spring of sufficient strength to 70 hold said guide 7 snugly in the groove 6. The ends of the plates 3 and 4 adjacent to the straight edge and the corresponding end of the strap 9 are deflexed underneath, the 75 bent back portions being bifurcated forming 80 fingers as 10, 10, which diverge as shown in Fig. 3, and rubber tips 11 are secured between said fingers. At the opposite ends of the plates 3 and 4, and depending therefrom, are the supporting legs 12 and 13, spaced 85 apart and having smooth rounded ends, the former of which are slightly longer than the latter so that when said legs 13 are touching upon a plane surface the rubber tips will be 90 elevated slightly above the surface. Thus 95 when an ink drawing is being made the rule can be slid on the legs 12 and 13 and the straight edge 2 brought to another position without smearing the undried ink with the rubber tips. The work can thus proceed 100 without waiting for the ink to dry thereby saving a great deal of time.

When the rule has been moved until the straight edge 2 is in position to rule the line to be drawn a slight pressure on the rubber 110 tips 11 will operate to press the paper or other drawing surface flatly against the sur-

face of drafting table or other sustaining surface, thus insuring a solid surface upon which to draw, and at the same time said tips 11 being of rubber prevent the rule 5 from slipping as it would have a tendency to do, because of the pressure of the pen or pencil or other drawing instrument against the straight edge.

The central rubber tip on the flexible 10 strap 9 is arranged to be laterally adjustable for the ruling of lines of varying lengths so that said central rubber tip and one of the other rubber tips will insure contact of drawing surface to sustaining surface underneath immediately at each end of the line 15 to be drawn.

A rule of this character is specially adaptable for use in the drafting of small figures where short divergent lines are being drawn 20 in ink and is more or less useful in various other kinds of drafting work.

What I claim is:

1. A rule consisting of an oblong body 25 having a straight edge, supporting legs depending therefrom which, when resting upon a plane surface, hold said straight edge above the said surface, one of said legs being movable lengthwise relative to the rule.

2. A rule consisting of an oblong body 30 having a straight edge, supporting legs depending therefrom, which, when resting upon a plane surface, hold said straight edge spaced above the surface, spacers depending from the rule underneath said straight edge, 35 and an upstanding knob carried by the rule.

3. A rule consisting of an oblong body having a straight edge, supporting legs depending therefrom, which, when resting

upon a plane surface, hold said straight edge spaced above the surface, and spacers depending from the rule underneath said straight edge, one of said spacers being movable. 40

4. A rule consisting of an oblong member having a straight edge, supporting legs depending therefrom and spaced apart, and also spaced from said straight edge and a spacer depending from the rule underneath the straight edge. 45

5. A rule consisting of an oblong member 50 having a straight edge, supporting legs depending therefrom and spaced apart, and also spaced from said straight edge and a plurality of spacers depending from the rule underneath said straight edge, one of which 55 is movable.

6. A rule consisting of an oblong member having a straight edge and a lengthwise groove, metallic plates secured to the respective ends of the rule, a guide slideable in 60 said grooves, a strap integral with the guide and whose free end extends underneath the straight edge, spacers arranged underneath the straight edge and depending from said plates and strap respectively, the latter of 65 which is movable and a pair of depending legs arranged at each end of the rule and integral with the corresponding plates and spaced from said straight edge.

In testimony whereof I have signed my 70 name to this specification in the presence of two subscribing witnesses.

ANDREW E. ANDERSON.
